CLAIM

The ornamental design for a baby's romper suit as shown and described.

DESCRIPTION

The file of this patent contains at least one drawing executed in color. Copies of this patent with color drawings will be provided by the Office upon request and payment of the necessary fee.

FIG. 1.1 is a front elevation view of a first embodiment of our new design for a baby's romper suit;

FIG. 1.2 is a rear elevation view of the first embodiment shown in FIG. 1.1;

FIG. 1.3 is another front elevation view of the first embodiment, with the baby's romper suit in an opened condition showing the inside thereof, including a seam which constitutes a bottom limitation of an interior pocket of the baby's romper suit;

FIG. 1.4 is a front elevation view of the first embodiment shown in FIG. 1.3, with a flap of the interior pocket in an opened condition and obscuring portions of the seam;

FIG. 1.5 is rear elevation view of the first embodiment shown in FIG. 1.3;

FIG. 2.1 is a front elevation view of a second embodiment of our new design for a baby's romper suit;

FIG. 2.2 is a rear elevation view of the second embodiment shown in FIG. 2.1;

FIG. 2.3 is another front elevation view of the second embodiment, with the baby's romper suit in an opened condition showing the inside thereof, including a seam which constitutes a bottom limitation of an interior pocket of the baby's romper suit;

FIG. 2.4 is a front elevation view of the second embodiment shown in FIG. 2.3, with a flap of the interior pocket in an opened condition and obscuring portions of the seam; and FIG. 2.5 is rear elevation view of the second embodiment shown in FIG. 2.3.

The romper suit includes a pocket system that upon insertion of light pads in the pocket system, when the romper suit is wrapped about a baby, a first pocket with a light pad is in proximity to the belly of the baby, and a second pocket with a light pad is in proximity to the back of the baby.

(Continued)

The first pocket in a closed configuration is shown in FIGS. 1.3 and 2.3 (left portion of the romper suit), and in a partially-opened configuration (for acceptance of a light pad) is shown in FIGS. 1.4 and 2.4. The second pocket in a closed configuration is shown in FIGS. 1.3 and 2.3 (right portion of the romper suit), and in a partially-opened configuration is shown in FIGS. 1.4 and 2.4.

The portions of the design shown in yellow in FIGS. 1.1-1.5 and 2.1-2.5 represent a yellow fabric of the outside of the romper suit and outer contours of the inside of the romper suit.

The portions of the design shown in white in FIGS. 1.1, 1.3 and 1.4 represent two semitransparent linings of the inside of the romper suit. The portions of the design shown in white in FIGS. 2.3 and 2.4 represent one of the semitransparent linings forming the inside and the outside of the pocket system of the romper suit. The portions of the design shown in pale yellow in FIGS. 2.1, 2.3 and 2.4 represent the other one of the semitransparent linings of the inside of the romper suit.

The portions of the design shown in light grey in FIGS. 1.3, 1.4, 2.3 and 2.4 represent contours of the pocket system of the romper suit. The thicker light grey line shown in full in FIGS. 1.3 and 2.3, and shown partially obscured by the partially-opened configuration of the pocket system in FIGS. 1.4 and 2.4, represent a welded portion of the two semitransparent linings in order to form a closed bottom to the pocket system, for example, a glue portion where the two semitransparent linings are glued to one another.
